US00D634267S

(12) **United States Design Patent**
Blain

(10) **Patent No.:** **US D634,267 S**
(45) **Date of Patent:** **** Mar. 15, 2011**

(54) **VEHICLE RECHARGE STATION**

(76) Inventor: **James David Blain**, Northville, MI (US)

(**) Term: **14 Years**

(21) Appl. No.: **29/368,273**

(22) Filed: **Aug. 20, 2010**

(51) **LOC (9) Cl.** **13-02**

(52) **U.S. Cl.** **D13/107**

(58) **Field of Classification Search** D13/106–110,
D13/118–119, 184, 199; D15/9; 320/103–115
See application file for complete search history.

(57) **CLAIM**

The ornamental design for a vehicle recharge station, as
shown and described.

DESCRIPTION

FIG. 1 is a perspective view embodying the ornamental
design of a vehicle recharge station constituting my new
design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view embodying a use application of
the ornamental design constituting my invention;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines shown in the drawings are included for the
purpose of illustrating environmental structure and form no
part of the claimed design.
